GEORGES BARBAUDY, OF MARSEILLE, FRANCE.

SUPPORTING DEVICE FOR AVIATION.

994,968.

Specification of Letters Patent. Patented June 13, 1911.

Application filed June 4, 1910. Serial No. 565,111.

To all whom it may concern:

Be it known that I, GEORGES BARBAUDY, engineer, a citizen of the Republic of France, resident of Marseille, Bouches-du-Rhône, France, have invented new and useful Improvements in Supporting Devices for Aviation, which improvements are fully set forth in the following specification.

The present invention relates to an improved supporting device for aeroplanes and which constitutes a rectangular plane carrying at its ends and arranged inversely one relatively to the other, two bends or rolls of variable size and conical in form arranged above the supporting plane.

The object of the invention is to provide an aeroplane or like apparatus with improved means for obtaining perfect stability for facilitating steering and for preventing falls.

The device as a whole is intended to carry goods or passengers in the air for traversing the ground, water-courses, lakes, seas, etc., or for scientific war-like or other apparatus with or without passengers, or experiments or for toys of similar form and of larger or smaller size constructed of any appropriate material.

The subject matter of the present invention is illustrated by way of example in the accompanying drawing, in which:

Figure 1 is a plan view of the supporting device. Fig. 2 is a side elevation of one of the supporting or stabilizing cones. Fig. 3 is an elevation of the rear of the supporting plane.

The supporting plane is constructed of light material of any suitable kind provided it is of sufficient strength.

The improved device consists of a supporting plane 1 of rectangular form and of any suitable size according to the load to be carried. This plane may be preferably straight or slightly concave. At the ends of the supporting plane two conical bends or rolls 2 and 3 are curved upward and inward toward each other. The cones 2 and 3 enhance the stability of the supporting plane 1 and if their sizes are varied, to differing degrees, they may be used to effect the direction in which the plane travels. The cones 2 and 3, the length of which is substantially equal to the longitudinal width of the plane 1, have their apexes arranged at the front end of the supporting plane and their base at the rear end of this

same plane. They may be secured to the supporting plane, or they may constitute a continuation thereof according to the method of manufacture employed. The front part 4 of the supporting plane 1 is slightly raised viz., to the extent of about 1/30 to 1/20 of its width according to the angle of attack of the air to be obtained for efficient operation of the aeroplane.

It will be readily understood from the following remarks that the cones 2 and 3 act upon the air as safety means for maintaining the equilibrium of the supporting plane 1 in its normal position in case of accident or impossibility of steering it.

It is to be observed that the outer walls of a cone when arranged at one of the ends of the wings of a supporting plane encounter the more or less regularly arranged or normal particles of the atmosphere and the pressure of these particles toward the rear becomes increasingly vigorous in proportion as the speed of the apparatus is augmented. The force of such action owing to the construction is transmitted almost entirely toward the rear of the supporting plane. The rear part of the supporting plane being thus maintained in its horizontal line of flight relatively to the front part it becomes obvious that the front part will have a tendency to rise. If the rear part which is retained by the conical arrangement horizontal relatively to the front part of the plane, should rise, the latter would in this case become directed much more speedily toward the ground in as much as the apparatus loses a part of the support of the plane, and as the weight of the appliances and motors are located in such a manner as to increase the velocity of the fall which becomes inevitable unless something immediately comes into action to stop this fall. It is such a fall that I propose to prevent by causing the front part of the apparatus to rise in all cases. By means of the arrangement of the more or less closed cones this function is performed and without the intervention of any mechanism whatever that might possibly be out of order when necessary for preventing a fall.

Taking into account that the resistance to forward displacement plays a large part in the art of aviation it will be understood that if one of my improved conical devices were fitted on the left hand side the apparatus would constantly turn toward the right; on

the other hand, if one of such cones were fitted on the right hand side the apparatus would constantly turn toward the left. Therefore in these conditions if the two cones are similar, the apparatus carried along by its head in forward weight would proceed straight ahead. Consequently, if when traveling at full speed the relative sizes of the cones are varied, the aeroplane will turn to one side or the other, according to the maneuvers, taking for its pivot or turning base the cone whose surface presents the greatest resistance in the air, the other side traveling quicker owing to this. This changing or varying of the size of the cones to the right and left can be performed in various ways. By their action at the end of the supporting planes these cones serve to impart stability and to effectively prevent falls.

The changes of direction in elevation, steering to the right, steering to the left, restarting forward, running or any adjustment of the aeroplane may be obtained by the means heretofore employed for aeroplanes or similar apparatus. Changes in direction may, however, be obtained in this type of aeroplane by enlarging or reducing the dimensions of the cones 2 and 3 by any suitable means. Left hand turns are made by opening out the right cone and right hand turns by opening out the left hand cone, by reversing the gear used for this purpose.

Forward travel in a straight line is effected by bringing the right or left hand cone (according to the maneuver that has just been effected) back into its normal position in such a manner as not to steer the

aeroplane either to the right or to the left, merely allowing the two cones to serve their purpose as safety cones.

The phenomenon arising during the turning will be readily understood. The cone at the extremity of the wing which is depressed as a result of the turn forms a point of support for the apparatus as a whole, while the cone which is situated in the turn at the upper end of the wing which arises, acts as a suspension hook.

Propulsion may be effected by any known means.

Having now particularly described and ascertained the nature of my said invention and in what manner the same is to be performed, I declare that what I claim is:—

1. An apparatus of the character described, comprising a plane having a substantially conical surface at each end, one side of each of said conical surfaces being a continuation of the surface of the plane.

2. An apparatus of the character described, comprising a plane having upon its upper part, at each end, a flexible substantially conical surface.

3. An apparatus of the character described, comprising a plane, said plane having flexible ends which are curved upwardly and inwardly of the plane to form incomplete conical surfaces.

In testimony whereof I have signed this specification in the presence of two subscribing witnesses.

GEORGES BARBAUDY.
